SWIM SUIT

Frank Mansueto, Chicago, Ill.

Application February 23, 1956, Serial No. 40,295

Term of patent 14 years

(Cl. D3—17)

Fig. 1 is a perspective view of the front and side of the swim suit, and

Fig. 2 is a rear view thereof.

The swim suit is illustrated as worn by a female figure shown in dotted lines in the drawing.

I claim:

The ornamental design for a swim suit, as shown and described.
